UNITED STATES PATENT OFFICE

1,933,779

CONTAINER

Frederick Westerbeck, University City, Mo.

Application January 26, 1931. Serial No. 511,208

1 Claim. (Cl. 220—54)

This invention relates to containers of the type wherein a portion of the container is torn to unseal and open the container. For example, a sheet metal can may be permanently sealed at the top and bottom, and provided with weak circumferential lines to produce a removable portion adapted to be torn from the can body.

One of the objects is to produce a simple and inexpensive container of this type, having its elements so combined with each other that the container can be easily manufactured, readily sealed, and conveniently opened. The closure is adapted to serve as a lid, or closure, for the can body when the container is sealed and also when the removable portion is torn from the container.

More specifically stated, an object is to produce a simple can body having a closure seat below the removable portion which is torn from the body, thereby eliminating the relatively expensive additional elements usually employed to form a seat for the closure when the can is unsealed.

The ordinary can body of this type includes a closure seat above the removable tearing strip, and the closure occupies this seat after the strip is removed. As a consequence, a separate element of some kind is ordinarily required to prevent removal of the closure seat when the strip is torn from the can body.

By providing a closure seat entirely below the removable tearing strip, I eliminate the separate, or additional, elements referred to above. The specific structure hereafter described includes other advantages which will be apparent to those skilled in this art.

With the foregoing and other objects in view, the invention comprises the novel construction, combination and arrangement of parts herein-after more specifically described and illustrated in the accompanying drawing, wherein is shown the preferred embodiment of the invention. However, it is to be understood that the invention comprehends changes, variations and modifications which come within the scope of the claim hereunto appended.

Fig. 1 is a side elevation of a sheet metal can embodying the features of this invention.

Fig. 2 is an enlarged horizontal section on the line 2—2 in Fig. 1, showing the vertical seam which extends from the bottom of the can to the tearing strip.

Fig. 3 is an enlarged horizontal section on the line 3—3 in Fig. 1, showing the tongue above the vertical seam.

Fig. 4 is an enlarged vertical section showing a portion of the can body and closure as they appear before the closure is connected to the can body.

Fig. 5 is an enlarged vertical section on the line 5—5 in Fig. 4, showing how the closure may be permanently united with the upper margin of the can body.

Fig. 6 is a view similar to Fig. 5, with the tearing strip removed and the closure seated on a portion of the can body entirely below the former location of the tearing strip.

I will now describe the accompanying drawing which illustrates one form of the invention.

The can body A may be connected to the bottom by means of a seam 6, in the usual or any suitable manner.

The closure B may be permanently united with the can body by means of an ordinary seam as shown at 7 in Figures 1 and 5. This seam includes a flange 8 on the closure interlocked with a flange 9 at the upper margin of the can body.

After the can has been filled, the air may be exhausted to create a vacuum, or partial vacuum, in the can body. The closure may be applied as shown in Fig. 4, and the flanges 8 and 9 may then be forced to the positions shown by Fig. 5, so as to form a seal at the junction of the closure and can body. However, the invention is not limited to these details.

The can body is weakened in circumferential lines 10 to provide a removable portion 11 adapted to be torn from the can body. As shown by Figures 1 and 3, a free tongue 12 extends from this removable portion, said tongue being adapted to receive a key or other device whereby the strip 11 is removed.

The vertical portion of the can body may be a single sheet of metal having its vertical edges 95 connected by means of an interlocking seam 13 (Figures 1 and 2) extending from the bottom of the can to the lower weakened line 10, where the vertical seam terminates and merges into plain lapped portions 14 and 15 united by solder 16 (Figures 1 and 3). These plain lapped portions 14 and 15 extend from the closure B to the upper end of the vertical seam 13. The free tongue 12 extends from the outer lapped portion 14, and this portion has an inclined edge 16 (Fig. 1) extending from the upper weakened line 10 to the closure.

A V-shaped recess is thus formed between the inclined edge 16 and the top of the tongue 12, and the point of this V-shaped recess is in

vertical alinement with the outer vertical fold in the seam 13, as shown in Fig. 1.

Since the lower edge of the tongue 12 extends from said vertical fold, while the upper edge extends from the point of the V-shaped recess, the tearing operation is positively started at the weakened lines 10.

I will now describe the closure and elements associated therewith as shown most clearly in Figures 5 and 6.

The closure includes a top wall 17 and a two-ply flange 18 connecting said top wall to the seam 7. The metal is folded at the lower edge of the flange 18 to provide a smooth rounded edge.

When the can is sealed, the closure extends into the can body and engages the inner face of the upper margin 19 which is permanently united with the closure. In the preferred form of the invention, the closure also engages the inner face of the removable tearing strip 11, as shown in Fig. 5.

It will be important to observe that the can body includes a closure seat 20 below the removable strip 11. An internal bead 21 is formed below the seat 20.

When the elements are arranged as shown in Fig. 5, the removable tearing strip 11 separates the closure from the seat 20, but when said strip is removed, the closure is detached and may be applied to the can as shown in Fig. 6, wherein it extends into the can body and frictionally engages said seat 20. The bead 21 then serves as a stop to limit the inward motion of the closure.

The simple can body includes the upper margin 19 permanently secured to the can body, the removable tearing strip 11 immediately below

said upper margin, and the auxiliary closure-seat 20 below the tearing strip. These simple elements can be conveniently made of the same diameter, corresponding to the diameter of the can body, without the use of any additional elements to receive the closure when the tearing strip is removed.

In other words, an ordinary simple can body of uniform diameter may be formed with the novel combination and arrangement of elements to produce a very simple key-opening can, having the advantages of more complex and expensive cans of this type.

I claim:

A container comprising a sheet metal can body having a closure united with its upper margin, said can body being weakened in circumferential lines to provide a removable portion adapted to be torn from the can body, said can body having an internal closure seat extending downwardly from its upper edge, across the inner face of said removable portion and into an area below said removable portion, said closure being provided with an integral two-ply flange folded at its lower edge, said integral two-ply flange being extended downwardly from its upper edge, across the face of and in contact with said removable portion, said integral two-ply flange being separated from the lower portion of said internal seat when the container is sealed, and adapted to engage said lower portion when said removable portion is torn from the can body, said can body being provided with an internal bead located below said lower portion of the internal seat and serving as a stop for the closure when said removable portion is torn from the can body.

FREDERICK WESTERBECK.
